UNITED STATES PATENT OFFICE

CHARLES C. CLIFFORD, OF COLERAINE, MINNESOTA

LIFEBOAT

Application filed April 6, 1929. Serial No. 353,070.

The invention primarily has for its object to provide a novel form of life boat adaptable for use upon any seagoing vessel, in parts because of its having qualities of being self-propelled, of providing complete shelter of its occupants from the elements, and of being non-capsizable, but which is particularly adapted for use upon submarines, there being means provided for transferring persons from the interior of a sunken submarine upon which it is mounted into the said life boat to enable their being carried in safety to the surface of the sea.

In its more detailed nature the invention resides in the provision of a wholly closed life boat having therein means to enable navigation under its own power, means also being provided for rendering the boat substantially non-capsizable.

Another object of the invention is to provide a novel means for securing the life boat upon a submarine in a manner for enabling quick release of the life boat from its mounting by occupants within the life boat, novel hatch equipments being provided through which occupants of the submarine may be transferred into the life boat.

Another object of the invention is to provide novel means cooperatively associated with the life boat mounting means for sealing the hatchways against water leakage and for providing a transfer passage between the interiors of the life boat and the submarine.

Other objects will in part be obvious and in part be pointed out hereinafter.

To the attainment of the aforesaid objects and ends the invention still further resides in the novel details of construction, combination and arrangement of parts, all of which will be first fully described in the following detailed description, then be particularly pointed out in the appended claims, reference being had to the accompanying drawings, in which:

Figure 1 is a somewhat diagrammatic longi-

tudinal section of my improved life boat, so much of a submarine being shown as is necessary to illustrate the mounting thereof.

Figure 2 is a vertical cross section taken on the line 2—2 on Figure 1.

Figure 3 is an enlarged vertical cross section taken on the line 3—3 on Figure 1.

Figure 4 is an enlarged vertical cross section taken on the line 4—4 on Figure 1.

Figure 5 is an enlarged detail section taken through the hatchway, both hatch covers being shown in place.

Figure 6 is an inverted plan view illustrating the life boat bottom hatch covers secured in position on its seat ring.

Figure 7 is a detail vertical cross section showing the life boat securing and jack nut released from the securing screw.

In the drawings, in which like numerals of reference indicate like parts in all of the figures, 1 designates the upper wall of a submarine, it being understood that while the invention may be used on any seagoing vessel it is particularly adaptable to use on submarines, and provides a means whereby the crew trapped in the vessel resting on the floor of the ocean may readily make their escape to safety.

The life boat is generally designated by the numeral 2 and it will be observed by reference to Figures 1 and 2 of the drawings that the same is in the nature of a wholly closed stream line body that will offer little resistance to travel through the water and which will afford full protection to its occupants from the elements.

The life boat 2 is provided with battery and motor equipment of any suitable design, generally designated 3 and serving to drive the propeller 4 to enable navigation of the same. The customary vertical rudder 5 is provided and in addition an elevating fin or rudder 6 is provided to facilitate rising of the life boat to the surface of the sea when re-

leased from its mountings upon the sunken submarine.

The elevating rudder 6 may be operated through any suitable device 7 from the look-out dome 8 which extends upwardly above the ceiling of the life boat in the manner illustrated in Figures 1 and 2 of the drawings and is provided with look-out windows 9 for a purpose that will be obvious.

10 The look-out dome 8 is open at its upper end and serves as a means through which ingress and egress may be had into and from the life boat. The dome is closed by a hatch 10 of any suitable construction and which is 15 preferably hinged to the said dome to prevent loss. It should be understood that the craft 2 may be employed on seagoing surface vessels and in this event the loading and unloading of passengers is occasioned 20 through the hatch 10 and dome 8.

Two or more tanks 11 are suspended from the ceiling of the craft 2 in the manner and position illustrated in Figures 1 and 2 of the drawings and these tanks are preferably 25 filled with a lighter-than-air gas. By reason of positioning the heavy motor or engine and batteries in the bottom of the craft and the tanks in the elevated position shown, the craft is caused to have a peculiarly low center 30 of gravity such as will cause it to ride easily and safely in rough seas. This equipment also renders it practically impossible to capsize the boat either during launching from the submarine or a surface vessel or 35 during travel in very rough seas. The provision of the tanks 11 also serve to greatly facilitate the rising of the craft to the surface when released from a sunken submarine.

One or more oxygen tanks 12 may also be 40 mounted in the craft 2 to sustain the crew housed within the craft until the said craft has safely risen to the surface of the sea when fresh air can be admitted through the hatch 10 with which the look-out dome 8 is 45 equipped.

An inverted U-shaped keeper 13 is secured in any suitable manner upon the deck of the submarine as indicated in Figures 1 and 4 of the drawings, and at a considerable 50 distance forward of the position of the keeper 13 a vertical screw shank 14 is pivotally mounted as at 15 upon the said submarine deck. The members 13 and 14 serve as part of the means for releasably securing 55 the life boat upon the deck of the submarine and for this purpose the screw 14, when in operation, passes upwardly through an opening provided in the life boat bottom and into a bracket 16 rigidly secured as at 17 to the 60 life boat floor, see Figures 1, 2, 3 and 7. The bracket 16 comprises a cylindrical body which terminates at its upper end in a gland 18 and is provided at its lower end with an abutment or bearing boss 19, see Figure 3.

65 A turning stem 20 projects from the top

of the bracket and is rotatable in the gland, and the said stem carries a handle wheel 21 at its upper end and a screw socketed head 22 at its lower end which is rotatable but held against longitudinal movement between the bearing boss 19 and the bearing shoulder 23 provided in the upper end of the bracket. Obviously, as the hand wheel 21 is rotated the screw 14 will be caused to move upwardly or downwardly into or out of the screw 75 socket and head 22.

A stepped finger 13^a is secured to the bottom of the life boat 2 and extends rearwardly in spaced relation to the said bottom to normally seat in the U-shaped keeper 13 in 80 the manner illustrated in Figures 1 and 4 of the drawings. More about this connection will be said later.

A seat ring 24 is secured on the upper face of the submarine deck 1 in any approved manner and the said ring is equipped with a suitable gasket 25 and an upstanding flange 26. The upper face of the gasket 25 is preferably covered with graphite to prevent sticking. A sealing ring 27 of a diameter 90 for seating upon the gasket 25 is secured in any approved manner to depend from the bottom surface of the life boat and this ring 27 and the ring 24 are preferably formed 95 of non-corrosive metal.

When the parts 13-13^a are positioned in association as illustrated in Figure 1 of the drawings and the bracket 16 and screw 14 properly associated as shown in the same figure, as the hand wheel 21 is turned clockwise the screw shank will be drawn up into the socketed head 22 and the said ring 24 and sealing ring 27 will be forced into tight liquid sealing contact as illustrated in the said figure and in Figure 5. Thus the life boat is not only effectively secured upon the submarine deck but the rings are securely clamped to prevent leakage into the passage formed within their annular limits. On the other hand when the hand wheel 21 is rotated 110 counterclockwise the screw 14 will be forcibly expelled from the head 22, the parts thus acting as a jack, and the rings 24 and 27 will be forced apart so that when power is applied to the propeller 4 the finger 13^a may 115 freely ride out of the keeper 13 so that the craft can ride to the surface in a direction forwardly and upwardly.

Cradles 28 are also secured, as at 29, upon the deck of the submarine and, as will be 120 observed by reference to Figure 2 of the drawings, are of inverted U-shape to receive the life boat 2 in conjunction with the securing means above described and further serve to hold the same in proper position upon the submarine deck against the strains set up 125 by travel through the water.

Within the ring 24 the submarine deck is provided with an opening 30 which is reinforced by a ring 31 secured, in any suitable 130

manner, to the deck and a similar but larger opening 32 is likewise provided in the life boat floor and is reinforced by a ring 33 suitably secured to the life boat floor. Each 5 of the rings are provided with a bevel clamp face 34 and each serves as a mounting or seat for a removable hatch cover 35 which may be constructed alike except for their difference in size, it being understood that an opening 10 through the floor of the life boat is large enough to permit withdrawal of the smaller hatch cover therethrough for a purpose that will be described later. The hatch covers each include gasketed seating flanges 36.

15 Each hatch cover has a vertical central bore 37 equipped with a gland 38 in which an operating shaft 39 is rotatably mounted. Each shaft carries a hand wheel 40 at its upper and lower ends so that one hand wheel 20 is disposed above and one below each said cover. Each shaft also carries a star wheel 41 to each point of which the inner end of a shifter arm 42 is pivoted, each said arm passing through a guide bearing 43 depending from the hatch cover and being equipped 25 with a cam head 44 having a bevel face for clamping engagement with the clamping face 34 of the reinforce and seating rings 31 and 33.

30 Thus when any one of the hand wheels 40 is rotated in one direction it will bring about retraction of the clamping fingers 42-44 and when rotated in the opposite direction will project the fingers to the active position clearly illustrated in Figures 5 and 6 of the drawings.

If desired the life boat 2 may be equipped adjacent its water line with longitudinal hold rods 45 to which survivors of a disabled ship 40 floundering about in the water may readily cling while awaiting assistance from within the craft.

In use, the life boat is secured upon the submarine in the manner illustrated in Figures 1 45 and 2 of the drawings, and the upper or life boat hatch cover 35 is preferably removed as illustrated in dotted lines in the said Figure 1. The hatch cover 10 of the look-out dome 8 is securely closed and the interior of 50 the life boat is, of course, secured against water leakage by reason of the clamping relation of the ring 24 and 27.

Should an emergency exist wherein a submarine was disabled and resting upon the 55 ocean floor it is only necessary to properly manipulate the lowermost hand wheel 40 to release the lower or submarine hatch cover 35 so that it can be forced upwardly through the opening in the bottom of the life boat and 60 into the interior of the life boat to open a clear-through hatchway or passage from the interior of the submarine into the interior of the life boat. After the crew has been safely removed the submarine hatch cover may 65 again be affixed to position by manipulation

of its uppermost hand wheel so that after leaving the submarine it may be sealed against water leakage and resulting damage prior to salvaging.

By now securing the life boat hatch cover to 70 position by manipulation of its uppermost hand wheel the bottom opening of the life boat may be secured against water leakage. By now manipulating the hand wheel 21 in the manner hereinbefore described the life 75 boat may be forcibly released from its securing means upon the submarine deck and by proper manipulation of the rudder 6 and the application of power to the propeller 4, the said craft may be safely driven to the surface 80 and thereafter safely navigate until other assistance is afforded.

From the foregoing description, taken in connection with the accompanying drawings, it is thought that the novel details of 85 construction, the manner of use and the advantages of my invention will be readily apparent to those skilled in the art to which it relates.

What I claim is:

1. The combination with a submarine boat, 90 of a life boat comprising a streamline normally closed body, a hatch by which access may be had to the interior of the body, hatches by which communication may be had between the boats, means to mount the life boat on the submarine boat with the hatches in associated relation, said last named means comprising a finger and eye connection toward the stern of the life boat and a jack screw toward the bow of the life boat.

2. The combination with a submarine boat, 95 of a life boat comprising a streamline normally closed body, a hatch by which access may be had to the interior of the body, hatches by which communication may be had between the boats, means to mount the life boat on the submarine boat with the hatches in associated relation, said last named means comprising a finger and eye connection toward the stern of the life boat and a jack screw toward the bow of the life boat, said jack screw being releasable from within the life boat.

3. The combination with a submarine boat, 100 of a life boat comprising a streamline normally closed body, a hatch by which access may be had to the interior of the body, hatches by which communication may be had between the boats, means to mount the life boat on the submarine boat with the hatches in associated relation, cooperating sealing rings surrounding said communication-effecting hatches, said last named means comprising a finger and eye connection toward the stern of the life boat and a jack screw toward the bow of the life boat, said jack screw being releasable from within the life boat, and so constructed and arranged as to be active in 105 one direction to force the sealing rings to- 110

gether and in another direction to force them apart.

4. In a structure of the character described wherein is provided a hatchway, a ring in the hatchway and having a clamping face, a hatch cover having a rotatable shaft extending through it and beyond each side thereof, means on each end of the shaft to impart rotation thereto, a star wheel on the shaft, a plurality of lock fingers each pivoted at its inner end to a point of the star wheel and each having at its outer end a clamp head to engage or disengage the clamping face of the hatch cover according to the direction in which the shaft is rotated, and bearings for the said lock fingers.

CHARLES C. CLIFFORD.
